R. H. ANKENY.
FLUSHING CUSPIDOR.
APPLICATION FILED MAY 27, 1921.

1,424,272.

Patented Aug. 1, 1922.

UNITED STATES PATENT OFFICE.

ROY HORACE ANKENY, OF MORGANTOWN, WEST VIRGINIA.

FLUSHING CUSPIDOR.

1,424,272.

Specification of Letters Patent. Patented Aug. 1, 1922.

Application filed May 27, 1921. Serial No. 473,138.

To all whom it may concern:

Be it known that I, ROY H. ANKENY, a citizen of the United States, residing at Morgantown, in the county of Monongalia 5 and State of West Virginia, have invented new and useful Improvements in Flushing Cuspidors, of which the following is a specification.

This invention relates to improvements in 10 cuspidors intended, primarily, for use in sick rooms, hospitals and the like.

An object of the invention is to provide a sanitary flushing cuspidor which may be readily placed in any suitable position, as, 15 for instance, adjacent a bed, and which may be flushed when desired without connecting the device to a water supply system, as is generally necessary in connection with devices heretofore known.

20 It is old and well known in the art to provide flushing cuspidors for the use of dentists and hospitals, in which the cuspidor is flushed directly from a water supply pipe connected to the main supply line 25 of a building. Obviously, such devices can be installed only by one skilled in the particular art, and when once installed cannot be moved about to other positions.

The present invention seeks to overcome 30 the above mentioned objections to the usual flushing cuspidor by providing a movable support which may be quickly placed in any convenient position, and upon which is located the cuspidor. The cuspidor is preferably 35 movable toward and away from the support, and is flushed by fluid from a container positioned on the support above the cuspidor. The cuspidor empties into a chamber also located upon the support, and 40 preferably removable from the support independently of the remainder of the device.

The invention also contemplates the provision of means whereby the limit of movement of the cuspidor away from the support 45 may be varied, and of means for supplying a disinfectant to the chamber receiving the waste from the cuspidor.

In the accompanying drawings there is illustrated one form of a device in which 50 the invention may be embodied, and in these drawings—

Fig. 1 is a front elevational view,

Fig. 2 is a sectional side elevation,

Fig. 3 is a detail plan view of the cuspidor bowl,

Fig. 4 is a cross sectional view of the bowl shown in Fig. 3, and

Fig. 5 is a detail view showing the closure plug and connecting nipples for the waste receiving chamber.

Referring to the drawings more in detail, like numerals indicating similar parts throughout, 10 indicates a platform having a standard 11 extending upwardly therefrom and provided with casters 12 permitting the device to be readily moved and suitably positioned, as beside a bed for use in a sick room.

Adjacent the top of the standard is secured a stand or bracket 13 which may be held in position by means of a stud 13' thereon passing through an opening 14 formed in the standard to receive a wing nut 15. It will be noted that the standard has formed therein a plurality of openings 75 vertically placed so that the bracket may be adjusted vertically when desirable. Upon the bracket is placed a container 16 to serve as a reservoir for flushing fluid. The container communicates through a valve 17 and 80 flexible pipes 18 with cuspidors 19.

It will be noted by an inspection of Figs. 3 and 4 that the pipes 18 connect with nipples 20 which conduct the fluid around the rim of the cuspidor bowl through a spraying pipe 21 formed with suitable openings 22, permitting the fluid to flush the bowl. The cuspidors are connected to drain pipes 23 into which the waste and flushing fluid 90 may pass through openings 24 formed in 95 the cuspidors, and the drain pipes empty into a waste receiving chamber 25 supported upon the platform 10. The receiving chamber 25 may be provided with a closure plug 26 in which are inserted nipples 27 corre-

85 sponding in number to the number of the cuspidor drain pipes, and connected to the drain pipes by means of flexible couplings 28. It may be observed at this point that the nipples 27 are formed with elbows 27' 100 within the chamber to form a trap and prevent the fumes from passing out of the container into the room, and if desired, each nipple, at its lower end, may be formed with a swinging gate or closure 29 which is 105 gravitationally held in closed position, and may be opened by the fluid emptying into the chamber.

The cuspidors may be normally held in position adjacent the support or standard 110

by means of extensible or elastic connections 30 secured to the standard, as at 31, and to the cuspidor bowls at 32, so that when the cuspidors are to be used they may be moved 5 away from the standard, as indicated in the drawing, by simply extending the connections, which automatically return the cuspidors to inoperative position when the cuspidors are released.

10 In order that it may be possible to vary the distance which the cuspidors may be moved away from the standard without lengthening the pipes 18, the flushing fluid chamber may be vertically adjusted by placing 15 the bracket stud 13' in higher or lower openings 14, as may be desired. Obviously, if the bracket is raised the cuspidor cannot be moved as far from the standard as when the stud 13' is positioned in an opening 20 lower than that indicated in the drawings.

For the purpose of regulating the amount 25 of flushing fluid conducted to the cuspidors the valve 17 may be adjusted, and by adjusting one of the secondary valves 17' in the branches leading to the respective pipes 18 it is possible to cut off or in any way regulate 30 the supply of flushing fluid to the cuspidors, individually. Obviously, the valve 17' or additional valves might be located in the supply pipes 18 in a position more convenient 35 for the user, who may then flush the cuspidor after each time it has been used.

The invention also contemplates the supplying 40 of a disinfectant to the waste receiving chamber, and for this purpose a bracket 32 is adjustably positioned upon the standard, as by stud 33 passing through an opening in the standard, and having thereon a nut 34. The bracket support has a disinfectant container 35 communicating with the waste chamber through a regulating valve 36 and pipe 37, which is connected to a nipple 38 in the plug 26. By adjusting the valve 36 the supply of disinfectant may 45 be readily regulated.

The waste chamber 25 may be held in position 50 on the platform as by means of a strap 39 having its ends 40 passing through an opening in the standard and held by a nut 41. This chamber is preferably removable independently of the remainder of the device, and may be taken from the support and emptied by simply removing the plug 26 and strap 39, a bail 42 being provided for 55 carrying purposes. In order that the chamber may be kept upon the support until it is practically full it may be provided with a vent pipe 43 which may extend to the exterior for the purpose of conducting the 60 fumes from out of the room.

It will, of course, be understood that both the disinfectant container 35 and the flushing fluid chamber 16 are similarly removable, as for filling purposes.

65 Obviously, the invention is not limited to

the details of construction herein set forth, or to the exact number of cuspidors provided in the illustrated form of the invention, variation in these details and specific features of construction being considered 70 within the scope of the invention as defined in the following claims.

I claim:—

1. A device of the class described comprising a support, a container for flushing fluid on said support, a cuspidor movable independently toward and away from the support, means for conducting fluid from said container to the cuspidor to flush the latter, a drain pipe for the cuspidor, a receiving chamber into which said drain pipe empties a disinfectant tank on said support, and means for supplying a disinfectant from said tank to said chamber. 75

2. A device of the class described comprising a support, a container for flushing fluid on said support, a cuspidor movable independently toward and away from the support, means for conducting fluid from said container to the cuspidor to flush the latter, 80 a drain pipe for the cuspidor, a receiving chamber into which said drain pipe empties, a disinfectant tank on said support, means for supplying a disinfectant from said tank to said chamber, and means for conducting 85 the fumes from the interior of said chamber. 90

3. A device of the class described comprising a support, a container for flushing fluid on said support, a plurality of cuspidors on the support movable toward and away from the support, conduits for conducting fluid from said container to said cuspidors to flush the latter, drain pipes for the cuspidors, a removable receiving chamber on said support into which said drain pipes empty, 100 said receiving chamber being removable independently of the remainder of said device, a disinfectant tank on said support and means for supplying a disinfectant from 105 said tank to said chamber. 110

4. A device of the class described comprising a support, a fluid container adjustably mounted on said support, a cuspidor angularly movable relative to said support, 115 means for conducting fluid from said container to the cuspidor, a receiving chamber having a removable closure plug mounted on said support, a drain pipe extending from said cuspidor to said chamber through 120 said plug, a disinfectant tank on said support, means passing through said plug for conducting a disinfectant from said tank to said chamber, and means in said plug for conveying the fumes from the interior of 125 the chamber for the purpose specified.

In testimony whereof I have hereunto set my hand.

ROY HORACE ANKENY.
